UNITED STATES PATENT OFFICE.

FRANK L. SLOCUM, OF PITTSBURGH, PENNSYLVANIA, ASSIGNOR TO JAMES HENRY REID, OF PITTSBURGH, PENNSYLVANIA.

PROCESS FOR THE FIXATION OF NITROGEN.

1,318,929.

Specification of Letters Patent. Patented Oct. 14, 1919.

No Drawing.

Application filed November 27, 1917. Serial No. 204,184.

To all whom it may concern:

Be it known that I, FRANK L. SLOCUM, a citizen of the United States, and resident of Pittsburgh, in the county of Allegheny and State of Pennsylvania, have invented a new and useful Improvement in Processes for the Fixation of Nitrogen; and I do hereby declare the following to be a full, clear, and exact description thereof.

10 My invention relates to the process of effecting a combination between nitrogen gas and a carbid whereby nitrogen-containing products are secured at lower temperatures and in shorter time than has been 15 possible heretofore.

This application is filed as a continuation in part of my application, Serial No. 190,565, filed September 10, 1917.

I produce the acceleration of the reaction 20 and the lowering of the necessary temperature by means of catalytic agents which may be used separately or combined in any ratio that may appear desirable. One class of catalysts consists of carbon-haloid compounds, such as carbon tetrachlorid, for example.

The carbid can be as such or mixed with a suitable amount (1 to 5%, for example) of alkaline salt—such as sodium carbonate—or 30 alkaline hydrates or oxids, or other compounds having great affinity for chlorin.

The second class of catalysts consists of the product resulting from the action of nitrogen upon a carbid. This nitrogen-carbon is an active auto-catalyst. For the purpose here described, it is immaterial whether this catalyst be formed in the presence of any other catalyst, or whether the material used be fully saturated with nitrogen or not, 35 as I have discovered that the admixture with a carbid of a nitrogen-containing material resulting from the action of nitrogen on a carbid and the subsequent exposure of the mixture to the action of nitrogen gas at 40 a suitable temperature results in the absorption of nitrogen at a lower temperature and in less time than is the case when carbid alone is exposed to the action of nitrogen.

In describing a particular method of procedure for carrying out my process, it is 50 understood that I may vary the steps of the method both in order and arrangement within the scope of the appended claims.

The method which I prefer to use for ac-

celerating the reaction by means of a carbon-haloid compound, such as carbon tetrachlorid, is as follows: A commercial carbid, as calcium carbid, for example, is reduced to powder and placed in a furnace of suitable design and heated to about 750° Cent. During this heating and until the end of the reaction, a current of nitrogen gas containing from 1 to 5% by volume of carbon tetrachlorid vapor is introduced into the furnace in such amount as to maintain a fairly constant pressure on the material and to prevent the access of furnace gases from the combustion chamber to the material.

When the conditions as stated above are carried out, the absorption of nitrogen takes place in about three hours, and the heat of the reaction is not as great as when the reaction takes its normal course and, therefore, the temperature of the mass does not reach a point where cyanids are formed. This is a valuable feature of the process, as the presence of cyanids in the final product is a decided disadvantage, since the production of ammonia is made more difficult, and if it is intended to use the product as a fertilizer the presence of cyanids (which are deadly poisons) may result in much injury.

A further advantage of the use of the particular catalyst here described is that, being perfectly mixed with the gas and being itself a gas under furnace conditions, it is thoroughly diffused throughout the system and acts in a more efficient manner than can be the case with a solid catalyst.

A solid catalyst can only act at its own surface, which is very small in comparison with the total surface of the carbid particles, unless so much of the solid catalyst be used as to result in the presence of a large amount of inert matter in the product.

The nitrogen-containing material resulting from the interaction of a carbid with nitrogen may be used as a catalyst as follows, though it is to be understood that I do not limit myself to the exact method of procedure or amount of catalyst here stated.

A carbid, as calcium carbid, for example, is crushed to about forty-mesh size and mixed with from 2 to 5% by weight of the powdered nitrogen-containing product obtained by acting on a carbid with nitrogen

gas at a temperature such that nitrogen is absorbed by and enters into combination with the metal of the carbid. This mixture is introduced into a suitably designed retort and the retort is maintained at about 750° Cent. during a period of four to six hours and an atmosphere of nitrogen gas maintained within said retort. The temperature of the mass is kept below 1000° 10 Cent., and the resulting product is saturated with nitrogen and is practically free of cyanides.

Whenever it is desirable, the two catalysts described above may be used in conjunction by exposing the mixture of carbid and nitrified material to nitrogen gas containing a carbon-haloid compound while maintaining the retort at a temperature of approximately 750° Cent. By using this 15 mixture, it is possible to get the greater acceleration due to a gas catalyst without the necessity of introducing more than 1 to 2% by volume of the gas catalyst into the nitrogen.

25 The use of the nitrogen-containing material as a catalyst has a very great advantage over all other solid catalysts, in that no inert material is left in the product as taken from the furnace, since the nitrogen 30 in the catalytic material is not lost by the reaction.

While I have indicated certain particular materials or compounds of materials which may be used in carrying out the invention, 35 and also have described the various steps of the processes which may be carried out, it is to be understood that the invention is not confined to the particular materials or compounds referred to, nor is it limited to the 40 exact order or arrangement of steps specified; but the invention is to be understood as comprehending the processes indicated in the appended claims without unnecessary limitation.

45 What I claim is:

1. The process for the fixation of nitrogen which consists in treating a carbid with nitrogen gas in the presence of a carbon-haloid compound used as a catalyst.
- 50 2. The process for the fixation of nitrogen which consists in mixing a carbid with a compound formed by reaction between a carbid and nitrogen as a catalyst, and treat-

ing the same with nitrogen in the presence of a carbon-haloid compound.

3. The process for the fixation of nitrogen which consists in introducing a carbon-haloid-vapor and nitrogen gas into a carbid, and maintaining the carbid at a temperature necessary to cause the required fixation.

4. The process for the fixation of nitrogen which consists in introducing carbon-tetrachlorid in gaseous form along with nitrogen gas into a carbid while maintaining the latter at a temperature for accomplishing the fixation of the nitrogen.

5. The process for the fixation of nitrogen which consists in introducing carbon-tetrachlorid in gaseous form along with nitrogen gas into a carbid while maintaining the same excluded from the air and at a temperature for accomplishing the fixation of the nitrogen.

6. The process for the fixation of nitrogen which consists in mixing a carbid with an alkaline salt, introducing a carbon-haloid vapor and nitrogen together into such carbid and salt and maintaining the mixture at a temperature to accomplish the fixation 75 of the nitrogen.

7. The process for the fixation of nitrogen which consists in mixing a carbid and a completely nitrified material, introducing nitrogen gas, and maintaining the compound at a temperature for the fixation of the nitrogen.

8. The process for the fixation of nitrogen which consists in treating a carbid with carbon-tetrachlorid, and introducing nitrogen gas while maintaining the compound at a temperature to cause the fixation of the nitrogen.

9. The process for the fixation of nitrogen which consists in mixing a carbid with an alkaline salt, treating the mixture with carbon-tetrachlorid, and introducing nitrogen gas to the mixture while maintaining the said mixture at a temperature to cause the fixation of the nitrogen.

In testimony whereof I, the said FRANK L. SLOCUM, have hereunto set my hand.

FRANK L. SLOCUM.

Witnesses:

J. M. DEVANEY,
W. J. BOLAND.

Certificate of Correction.

It is hereby certified that Letters Patent No. 1,318,929, granted October 14, 1919, upon the application of Frank L. Slocum, of Pittsburgh, Pennsylvania, for an improvement in "Processes for the Fixation of Nitrogen," were erroneously issued to James Henry Reid, of Pittsburgh, Pennsylvania, whereas said Letters Patent should have been issued to *International Nitrogen Company, a Corporation of Delaware*, said corporation being assignee, *by mesne assignments*, of the entire interest in said invention, as shown by the records of assignments in this office; and that the said Letters Patent should be read with this correction therein that the same may conform to the record of the case in the Patent Office.

Signed and sealed this 17th day of April, A. D., 1922.

[SEAL.]

KARL FENNING,

Acting Commissioner of Patents.
